UNITED STATES PATENT OFFICE.

ELMER E. VAN WIE, OF LOS ANGELES, CALIFORNIA.

BUILDING CONSTRUCTION.

Application filed October 27, 1923. Serial No. 671,098.

To all whom it may concern:

Be it known that I, ELMER E. VAN WIE, a citizen of the United States, residing at Los Angeles, in the county of Los Angeles and State of California, have invented a certain new and useful Improvement in Building Constructions, of which the following is a full, clear, and exact description, reference being had to the accompanying drawings.

This invention relates to building blocks or tile which are adapted to be arranged to form a wall or other building structure.

The general object of the invention is to provide an improved building block which is of such a nature that the block can be readily manufactured and easily assembled.

One of the specific objects of the invention is to provide a building block comprising a member having outer and inner planar faces with locking means uniting said faces and disposed at right angles to such faces in such a manner that a plurality of the blocks can be interlocked.

Another object of the invention is to provide a wall constructed of a plurality of interlocked hollow blocks wherein the blocks are united to form a monolithic structure having dead cells therein.

An additional object of the invention is to provide a tile comprising a rectangular block having four planar outer surfaces and having a central cylindrical cavity therein and wherein the block is provided with tongues, which may be removed to provide interlocking portions.

Other objects of the invention will be apparent from the following description taken in connection with the accompanying drawings wherein Fig. 1 is a perspective view of a portion of a wall constructed from blocks embodying the features of my invention; Fig. 2 is a perspective view of a full block; Fig. 3 is a perspective view of a half block; Fig. 4 is a perspective view, partly in section, showing a column constructed from my blocks; Fig. 5 is a perspective view, partly in cross section, showing another embodiment of my invention; Fig. 6 is a sectional view of a corner block; Fig. 7 is a perspective view, partly in section, showing another type of wall; Fig. 8 is a perspective view of a mold used in connection with my invention; Fig. 9 is a section showing another embodiment of my invention; Fig. 10 is a top plan view showing the

method of assembling the blocks; Fig. 11 is a sectional detail and Fig. 12 is a perspective view of two interlocked blocks.

Referring to the drawings by reference characters, I have shown at 10 a building block embodying the features of my invention. This block is shown as provided with a plurality of planar outer faces 11, 12, 14 and 15. The inner portion of the block is shown as provided with a central cylindrical aperture 16. The portion of the block intermediate the faces 11, 12, 14 and 15 is shown as having the outer surface 18 thereof arcuate and with the radius of curvature 60 coaxial with the center of the aperture 16. This construction provides a block having four protuberant faces, one of which may form the inside portion of a wall and the outer face may form the outside portion of 65 the wall.

The portions 18 may be provided at each end with pairs of parallel slits 19 thus defining tongues 20. The tongues 20 may be removed from the block when desired to 70 form notches which allow the blocks to be interlocked.

The blocks described may be made of a great number of materials. I find, however, that by making the blocks of clay that a 75 highly efficient product is secured, although I wish it to be understood that the blocks may be made of cement, plaster, indurated wood fibre, or any other material adapted to be formed into the shape shown.

In forming a wall I prefer to use half blocks as shown in Fig. 3 and full blocks as shown in Fig. 2. It is also desirable to provide a corner block and I have accordingly shown one at 21 which differs from the 80 other units only in that the faces 22 and 23 are plane throughout, the corner portion 18 being omitted.

The portions 18 and the resultant notches 85 19 are of sufficient width that when the 100 blocks are laid in a wall as shown in Fig. 1 that the contiguous edges may be united as at 25 to form a flush joint on both the inner and outer surfaces of the wall. When the blocks are so united there is considerable 105 space formed between the adjacent webs 26 as shown in Fig. 1.

When it is desired to curve the wall, as for instance, in building a silo, the contiguous edges as at 27 of one face may be abutted while the edges 28 on the other face may be spaced apart as shown in Fig. 1. When

this arrangement is produced the edges of the webs 29 will be arranged close together while the edges at 30 will be separated for a distance.

5 At 31 the wall is shown with a reversed curvature with the edges 32 arranged adjacent each other and the edges 33 spaced.

I prefer to place a cementitious filling within the cavities of the blocks shown in 10 Fig. 1 to provide a monolithic wall. It is also desirable to provide dead air cells within the walls for purpose of insulation, and in order to do this, I show a mold member 34 in Fig. 8. The mold member comprises 15 preferably a rigid wood body portion 35 which tapers toward its lower end so that it can be readily withdrawn. Upon the body 35 I secure opposed curved plates 36. The curved plates are preferably made of 20 metal and while being flexible nevertheless have sufficient rigidity to hold themselves in position within a block when inserted in place. The molds 34 are shown in both 25 block A of the straight wall and block B of the curved wall. In using the molds the cement is placed against the outer surface of the curved plate 36 and after the cement has hardened the mold member can be readily withdrawn.

30 In Fig. 4 I show at 40 a pier, or column, constructed from two rows of my improved tiles. In so constructing a column the tongues 20 are allowed to remain in the tile and preferably the hollow tile is filled with 35 cement so that a very efficient supporting member is afforded.

In Fig. 5 I show a tile 41 comprising a plurality of rectangular slabs 42 preferably made of cement and having embedded therein, and spaced from each end, reinforcing members 43. In constructing the tile shown in Fig. 5 I preferably mold the slabs 42 in order. To do this a mold of the proper size is filled with cement and a pair of reinforcing members 43 are embedded therein. After the slab has cured another slab is molded in a plane at right angles to the first slab and the process is repeated until the tile is complete.

50 In Fig. 6 I show a corner block which is of the same character as the block shown in Fig. 5. In this corner block instead of providing four separate slabs I prefer to use two separate slabs 44 and an L-shaped member 46. The reinforcing rods 47 preferably pass through both of the faces of the L-shaped portion and may be exposed at 48 or covered with cement at this point as desired.

60 In Fig. 7 I show a wall constructed of tiles of a slightly different character. The tiles here shown comprise preferably outer and inner members 50 and 51. The outer and inner members are shown as united by 65 securing means which include preferably

wooden planks 53 and 54. The planks are secured to the outer and inner members by means of suitable fastening means 55. I now prefer to construct the tile shown in Fig. 7 by first taking the planks of wood 53 and 54 and driving therein at suitable spaced distances from each end of the planks nails or spikes 55. This having been done I prepare a mold and after the mold has been filled with cement or other material I 70 insert the ends of the nails of two end members in the cement and allow it to set. After the cement has set I complete the other side of the tile in the same manner.

In constructing a corner block of the type 75 shown in Fig. 7 I preferably unite two of the locking members 60 as shown by means of a long metal reinforcement 61 and also provide suitable nails or reinforcements 63 and 64 similar to the reinforcement 55. I 80 then cast an L-shaped corner member 66 and embed the ends of the nails 60 therein.

In all of my tile herein described I provide full blocks and half blocks so that the 85 usual type of checker board wall will be 90 constructed. In building the wall shown in Fig. 7 I first set up the tile and interlock them as shown. I then pour the cement in the corner C after which I proceed to provide dead air cells within the wall by means 95 of the mold member 35. The mold member is shown as being used in making the cavity D, Fig. 7, and after the cement has partially set the mold member is withdrawn.

100 Instead of casting the faces of the tile shown in Fig. 7 with the reinforcements 55 embedded therein, I may precast the outer faces 70 of the tile as shown in Fig. 11 and provide them with rabbets 71. After the faces have cured I may insert the nails 55 105 in the rabbets and then insert a filling of cement 72 which on hardening will secure the nails 55 in place.

110 In Fig. 9 I have shown a portion of a wall constructed of tiling wherein all of the members are made of wood. The interlocking members 75 are united to the front and back 76 and 77 by driving spikes 78 through the faces of the members 76 and 77 and into the locking members 75. The wall shown in Fig. 9 may be completed by 115 inserting the filling of cement therein and dead air cells may be provided by use of the mold 35 if desired.

120 The tiles I have described as made partially of wood are particularly adapted for the use of farmers and other persons who are not equipped to make the whole clay or the whole cement tile. By utilizing my invention scrap lumber may be worked up into a great many useful articles and the tiles embodying the features of my invention are so easy to construct that the services of a 125 skilled mechanic at high wages are unnecessary, thereby allowing the farmer or laborer 130

to construct his buildings at a minimum of cost.

In Fig. 10 I show a wall 80 similar to that shown in Fig. 1. The wall is provided along each side with a reenforcing rod or wire 81 which passes through the notches 82 in the interlocked tiles 83. In order to align the wall it is merely necessary to pull tightly on the wire 81 thereby causing the tiles to shift until the outer and inner faces are in parallel planes. After this is done, and while the wire or rods remain tight, a filling of cement may be placed about the rods 84 thereby securing the reenforcement in place and making a monolithic structure of the wall. The dead air cells 85 previously described may be made by means of my mold 35.

In Fig. 12 I have shown an elevation of two interlocked blocks 88 and 89. The block 88 is a full length block while the block 89 is of a half length. It will be noted that the interlocking members 90 of the block 88 are of the same length as the front and back of the block while the interlocking members 91 of the half block are the same length as the front and back of the half block.

From the foregoing description it will be apparent that I have provided an improved type of building block from which monolithic walls for buildings, curved walls for silos, columns, piers, etc. can be economically constructed. The individual units can be very readily made by machinery or by hand and can be very economically assembled.

Having thus described my invention, I claim:

1. A wall constructed from a plurality of like units, each unit comprising rectangular front and back members, said front and back members being united to each other at each side thereof by locking members, said locking members of units in the same course interfitting, there being a space between the locking members of adjacent units to form an air cell within the wall, said wall having cementitious material thereon engaging the adjoining faces of the tile to hold them in assembled position and to thus seal the air cells within the wall.

2. A building tile comprising a rectangular body composed of four rectangular planar outer surfaces arranged at right angles to each other, said body having a cylindrical aperture extending therethrough, a pair of slits at each corner and at both ends of the rectangular body, said slits ter-

minating at spaced distances from the ends of said body thereby defining a tongue, the space normally occupied by said tongue serving to form interlocking notches when the tongues are removed and the block is placed in the wall, the inner surface of said tongues being arcuate and having the same radii as that of the cylindrical aperture.

3. A wall constructed from a plurality of like units, each unit comprising a rectangular front and back member, locking members secured at each side of the front and back members, the locking members of units in the same course interfitting, there being a space between the locking members, a filling of cementitious material occupying a portion of the space between the front and back faces, whereby a dead air cell is provided within the wall.

4. A wall comprising a structure formed from a plurality of similar tiles, each tile comprising a body portion having an outer and inner planar face and having notches in the ends thereof, the notches of adjacent tiles being interfitted to lock them together, a reenforcement extending through said notches, said reenforcement when tightened serving to align said tiles.

5. A wall constructed of tiles, each tile including front and back members and side members and having notches in the ends thereof, the notches of tiles in the same course being interfitted to lock them together, a reenforcement extending through said notches, said reenforcement when tightened serving to align said tiles, and a filling of cementitious material surrounding said reenforcement to hold the tiles and the reenforcement in position.

6. A wall built of a plurality of similar units, each unit comprising a body portion having front, back and side members, there being a space between each two members, at the ends thereof to form a notch, the notches of the units in the same course being interfitted to lock them together, a reenforcement extending through said notches, said reenforcement when tightened serving to align said units, and a filling of cementitious material surrounding said reenforcement to hold the latter in position, said units being hollow, said wall having a plurality of dead air cells therein, said dead air cells being arranged within the cementitious filling.

In testimony whereof, I hereunto affix my signature.

ELMER E. VAN WIE.
